UNITED STATES PATENT OFFICE.

ERNST G. K. ANDERSON, OF CHICAGO, ILLINOIS, ASSIGNOR TO ANDERSON ELECTRIC SPECIALTY COMPANY, OF CHICAGO, ILLINOIS, A CORPORATION OF ILLINOIS.

ACTUATING MEMBER FOR SWITCHES.

1,349,251.08

Specification of Letters Patent. Patented Aug. 10, 1920.

Application filed May 29, 1918. Serial No. 287,200.

To all whom it may concern:

Be it known that I, ERNST G. K. ANDERSON, a citizen of the United States, and a resident of Chicago, in the county of Cook and State of Illinois, have invented certain new and useful Improvements in Actuating Members for Switches; and I do hereby declare that the following is a full, clear, and exact description thereof, reference being had to the accompanying drawings, and to the characters of reference marked thereon, which form a part of this specification.

This invention relates to a novel actuating device for switches of that kind shown in my prior application for United States Letters Patent Serial Number 226,419, filed April third, 1918.

In the device shown in said application, the actuating member by which the switch is manually controlled is so mounted as to have a universally swingable movement about its pivotal connection with the frame of the switch, and to be axially displaceable, either of which movements is transmitted from a flat seat on the actuating member to an engaging plate or member constituting part of the switch control.

The purpose of the present invention is to provide a separable actuating member, one portion of which is pivotally connected to and slides in the switch frame and is adapted to receive either one or two terminal elements, one of which is fitted with a pendent chain, by pulling which the actuating device may be swung in any direction to operate the switch, and the other terminal element is furnished with a push button effect, to be used when the actuating device is axially displaced to operate the switch and also to be used when the actuating member is tilted, as by a side swipe with the hand.

Another object of the invention is to arrange the separable elements of the actuating device so as to be able to vary the length thereof and consequently the leverage exerted therethrough, when operating as a lever, to control the switch.

The invention consists in the combination and arrangement of the parts shown in the

drawings and described in the specification, and is pointed out in the appended claims.

In the drawings, Figure 1 is a plan view showing the general construction of the switch and illustrating one form of the actuating device.

Fig. 2 is an enlarged view, partially in section and partially in elevation, of the actuating device shown in Fig. 1.

Fig. 3 is a similar section showing a modification.

Fig. 4 is a view, partially in elevation and partially in section, showing the actuating device equipped with a push terminal.

The base 10 of the switch, the fixed and stationary switch elements 11, 12, respectively, the rocking, spring-actuated, switch throwing device 13, the plunger element 14, the frame 15 in which it slides, and the controller member 16 are made like the same parts illustrated in my prior application and need not be further described, except to state that reciprocation of the plunger element 14 acts, through the controller member 16 and the rocking switch throwing device 13, to alternately open and close the switch between the elements 11 and 12.

18 designates the actuating device which is manually operable to actuate the plunger element 14 and the parts associated therewith. It is a tubular structure and extends through an opening in the frame 15, the opening being of such size relatively to the diameter of the actuating device as to permit the latter to swing in all directions and also to permit it to slide axially inwardly. The said actuating device is provided inside the frame with a flat seat 19 which engages with an opposing flat seat formed on the plunger element 14 in the same manner as shown in my aforesaid prior application.

Referring more particularly to Fig. 2, it will be observed that the actuating device 18 consists of two tubular, preferably sheet metal, parts, the inner permanent part 20 and the outer removable part 21. The outer part 20 is closed by an end wall 22 that is centrally pierced to receive a rivet 23, or other fastening means by which the contact

seat member 19 is attached to the inner member of the actuating device. The outer member of the actuating device is made of a size to slide into the permanent inner member thereof, and said parts are formed so that the outer member may be removed from the inner member and the parts may be detachably locked together. The outer, detachable member of the actuating device is 10 closed at its outer end by an end wall 24 and is fashioned to receive a pull chain 25 of any suitable form.

The telescopic members 20 and 21 of the actuating device may be locked together in 15 any suitable or preferred way, but preferably by means which permit of ready detachment of the detachable member. As shown, the locking of said members together consists in providing one of the members with one or more beads, and the other member with corresponding annular groove or grooves; and one of the members, preferably the outer member, is formed with means to cause the wall thereof to expand 20 outwardly so as to force the registering grooves and beads into locking engagement. As herein shown and preferably, the outer member 21 is provided with an external bead 26 which is adapted to register and 25 interlock with an internal groove 27 on the inner or permanent member 20. The means for causing the wall of the outer member to expand consists in making said member of spring metal and longitudinally slitting it at one or more points 28; the arrangement 30 being such that the slitted end of the detachable member is compressed in order to permit it to enter the outer end of the permanent member, and the resiliency of the 35 metal forces the wall outwardly to produce the interlocking effect before mentioned.

In some instances the detachable and permanent members of the actuating device are formed with a number of interlocking beads 40 and grooves longitudinally spaced therealong. As shown in Fig. 2, the inner permanent member is formed with a second annular groove 30 to receive the bead 26 when the detachable member is forced inwardly to 45 bring said interlocking parts into register, and the detachable member is formed with a second bead 31 to engage with the groove 27 of the permanent member 20 when the detachable member is in its innermost position. In Fig. 3 the inner permanent member 32 and the outer detachable member 33 are provided with three of such interlocking 50 grooves 34 and beads 35, respectively.

This construction and arrangement permits the length of the actuating device to be 55 varied and consequently the leverage thereof, when acting as a lever, to be correspondingly varied. Furthermore, the interlocking connection provides a more reliable connection between the two parts of the actuat-

ing device when two or more of the interacting beads and grooves are engaged.

In Fig. 4 is shown the form which the actuating device assumes when used as a push button. As shown in said figure, the inner 70 permanent member 20 of the device is the same as that shown in Figs. 1 and 2. The outer detachable member 36 in this instance comprises a short tube which is open at its inner end and is slotted at 37 to enter the 75 inner permanent member 20. Said detachable member is also provided with a bead 35 to engage with the inner groove 30 of the permanent member. The detachable member 36 is formed at its outer end to provide 80 a solid disk 39 which is of a diameter to extend radially beyond the telescoped tubular members of the actuating device when the parts are assembled. When the detachable member 36 is employed, the switch is 85 operated by pushing the actuating device inwardly in the manner of a push button, although said actuating device may be operated by swinging it on its pivot in the same manner as when using the pull chain 25. 90

I claim as my invention:

1. An actuating member for an electrical switch and the like comprising a permanent tubular swingable and axially displaceable member, and a terminal extension member 95 telescopic thereon, with means to lock the extension member on the permanent member when extended at definite distance from the permanent member.

2. Actuating member set forth in claim 1, 100 characterized in that the permanent member has at its inner end an actuating element enlarged in a direction transverse to the axis of the actuating member.

3. Actuating device set forth in claim 1, 105 characterized that the permanent member is tubular to receive the terminal extension member, and that the latter member has a part designed to transmit manual power to the actuating device to actuate the latter. 110

4. Actuating member set forth in claim 1, characterized in that both the permanent and extension members are formed of sheet metal tubular construction, and that said members bear longitudinally spaced interacting locking means to hold the extension member extended. 115

5. Actuating member set forth in claims 1 and 4, wherein the interlocking means are grooves one the one part and beads on the 120 other part, and one of the parts is longitudinally split.

6. An actuating member for an electrical switch and the like comprising a permanent swingable and axially displaceable member, 125 and a terminal extension member telescopic thereon, the end of the latter member having an opening to receive the terminal of a pull strand.

7. An actuating member for an electrical 130

switch and the like comprising hollow telescopic members, with means to lock them in definite axial relation, one of said members having at one end an actuating element enlarged at right angles to the axis of said member, and the other member having at 5 the opposite end of the actuating member

an element through which manual power is transmitted to said actuating member.

In testimony whereof I claim the foregoing as my invention, I hereunto append my signature at Chicago, Illinois, this 17th day of May, 1918.

ERNST G. K. ANDERSON.
